LUBRICATING DEVICE FOR RAILWAYS

Charles Stern, Jersey City, N. J., assignor to Ardco Manufacturing Company, Hoboken, N. J., a corporation of Delaware

Application October 31, 1935, Serial No. 47,695

3 Claims. (Cl. 184—3)

The present invention relates to improvements in lubricating devices for railways, and more particularly refers to a device for lubricating the railway track rails adjacent curves whereby to reduce 5 friction of the flanges of the wheels upon the sides of the rail heads when the cars are rounding curves.

The invention consists in certain improvements in the track applicator which receives the lubricant from a source of supply and directs it upon the side of the rail head, such applicator being novel in the construction which enables it to deliver the lubricant in an elongated thin ribbon or sheet alongside such rail head.

Another object of the invention, so far as the rail applicator is concerned, is the arrangement by which a lubricant chamber within the applicator body is in alignment with the elongated narrow slot from which the ribbon or sheet of lubricant 20 emerges upon the side of the rail head.

A further object of the invention is to provide an improved reservoir for the supply of the lubricant which will retain the body of lubricant under constant pressure and which will enable the restoration 25 of the parts to the initial position ready for refilling with ease and efficiency.

A still further object of the invention is to provide an improved form of pumping and lubricant controlling device whereby quantities of the lubricant 30 will be supplied to the applicator in proportion to the amount of traffic traveling over the road.

With the foregoing and other objects in view, the invention will be more fully described herein- 35 after, and will be more particularly pointed out in the claims appended hereto.

In the drawings, wherein like symbols refer to like or corresponding parts throughout the several views,

Figure 1 is a fragmentary top plan view of a railway with the improved device shown applied thereto.

Figure 2 is a cross section through the railway with the improved device shown in elevation.

Figure 3 is a top edge view, with parts broken away of the improved applicator.

Figure 4 is a side elevation of the same, with parts broken away and parts shown in section.

Figure 5 is an end view of such applicator.

Figure 6 is a cross section taken on the line 6—6 in Figure 3.

Figure 7 is a cross section taken on the line 7—7 in Figure 3.

Figure 8 is a fragmentary side view of one of

the rails with the improved pump device shown applied thereto partly in section.

Figure 9 is a vertical section taken on the line 9—9 in Figure 8.

Figure 10 is a top plan view of the device 5 shown in Figures 8 and 9.

Figure 11 is a front elevation of the lubricating reservoir.

Figure 12 is a horizontal section taken on the line 12—12 of Figure 13.

Figure 13 is a side elevation of the reservoir with parts broken away and parts shown in section, and

Figure 14 is a fragmentary side view showing a modified form of the latch.

Referring more particularly to the drawings 15 and 16 represent the rails of a railroad over which rolling stock is adapted to travel on the wheels indicated in dotted lines at 17 and 18 in Figure 2, the wheels having the internal flanges 20 19 and 20 engaging the inner sides of the rail heads.

The outside rail 16 on the curve receives the thrust of the flanges 20 of the wheels 18 there-against as the rolling stock moves around the 25 curve so that it is the inside face of the rail head of the outer rail of the curve that requires lubri- cation.

In Figures 1 and 2, the improved applicator is shown as applied in this position upon the outer 30 rail 16, the applicator being connected with its source of oil or grease supply through the tube or pipe connection 21'.

The improved applicator is illustrated more particularly in Figures 3 to 7 inclusive. In these 35 figures a body or casting 21 is shown having a lubricant chamber 22 therein. The casting is formed of metal or other suitable material and the chamber may be cored out or otherwise produced. An upwardly extending lip wall 23 rises 40 from the casting along one side wall of the chamber 22 and extends alongside of the rail head 16. A removable cover plate or strip 25 is disposed opposite the lip wall 23 and spaced slightly there- 45 from to produce an elongated continuous channel or mouth open at its upper end adjacent the side of the rail head and communicating below directly with the chamber 22. The mouth 24 is preferably vertically above the chamber. The cover plate 25 is carried by, or has formed there- 50 on, a bead or flange strip 26 seated in a cavity 26' of the casting 21. The upper surface of the bead 26 is preferably flush with the shelf 27 of the casting, this shelf being cut down from the lip 23 to accommodate the flanges of the car wheels. 55

The cover plate 25 or outer wall of the lubricant slot 24 is preferably of hardened steel so that it will normally maintain its proper position and alinement against collapse inwardly toward the 5 lip wall 23, but which at the same time will withstand any strain or stress of the car wheel flange when passing thereover. The mouth or slot 24 will deliver the lubricant in a thin flat sheet or ribbon against the upper portion of the side of 10 the rail head 16, whereby such lubricant is picked up by the flanges 20 of the wheels 18 and carried about onto the curve for the purpose of lubricating the flanges and the rail head.

The body of the applicator is provided with 15 bosses 28 and 29 for fitting up against the web 30 of the rail.

Centrally of the device is an elbow 31 or other inlet connection for the lubricant, which connection is coupled to the supply pipe or tube 21' 20 shown in Figures 1 and 2.

The body or casting 21 of the applicator is secured to the web of the rail by means of extensions 21^a at each end of the applicator; such extension being provided with an elongated hole 22^a 25 to permit of vertical adjustment and through which the bolts 22^b pass. Lugs 37 are parts of the extensions 21^a and are located at each end of the applicator body or casting 21. The guard plates are provided with elongated holes 34^a in 30 registry with the holes 22^a of the extensions. Such guard plates are fastened on the extensions by means of screws, bolts or other fastening devices 35. The lugs 37 are threaded to receive screws 38, the head or other ends of which are 35 adapted to engage against the flange 39 of the rail for the purpose of adjusting the vertical height of the device including lip 23 with reference to the tread of the rail and with respect to the flanges 20 of the wheels 18.

Grease is supplied to the applicator through 40 the pipe 21' which pipe connects with a pump device carried near the companion rail 15, as shown in Figures 1 and 2. This pump device is shown in Figures 8, 9 and 10 and comprises generally a body 40 of cast metal or other suitable construction having a lower chamber 41 with a 45 port 42 for the discharge of the lubricant into the tube or pipe 21'. A second threaded opening in the lower wall of the device is closed by a threaded 50 plug 43.

This plug 43 is in alinement with a valve assembly and by removing the plug 43 the valve stem 44 and the valve 45 may be pushed up into the place occupied by these parts, as shown in Figure 55 8. The valve 45 is normally urged upwardly by a coil spring 46 into a closed position against the valve seat 47 surrounding a port 48, which port is made in the diaphragm or septum 49 extending horizontally across the body or casing 40. Above 60 this septum is a chamber supplied with lubricant by a tube or pipe 50 entering a port 51 of the casing 40. The valve stem 44 is carried by a plunger 52 which plunger reciprocates in a cylinder 53 formed in the upper portion of the casing 65 40 above the port 48. The coil spring 46 takes against the valve 45 at its upper end and at its lower end engages the plug 43. The plunger 52 carries a hollow threaded stem 54 supporting a threaded button 56. By rotating the button 56 70 its threaded shank 56^a will traverse the threads in the socket of the hollow stem 54, thus adjusting the button 56 as to its height with respect to the car wheel 17. The height of the plunger will control the throw or extent of the vertical motion 75 of the plunger 52 and of the valve 45 and the

amount the port 48 is opened. A key or set screw 57^a may be used to secure the button 56 against rotation after adjustment. The casing 40 is carried by a plate 59 secured by bolts or other fastening means 60 to the web of the rail 15.

This pump device receives its supply of lubricant through the pipe 50 from a reservoir shown more particularly in Figures 11, 12 and 13. The reservoir includes a container 61 open at its bottom to slide down over a fixed plunger 62 having 10 a packing cup 63 secured thereto and extending along the wall of the container 61.

At its upper end the container is closed by a removable cover 64 to admit of the introduction 15 of the lubricant into the container body.

The plunger 62 is stationary, being carried by a support 65 upstanding from a base or pedestal 66. The plunger is preferably concave to an opening 67 to which is connected the pipe or conduit 50.

Projecting from the sides of the movable container 61 are the ledges 68 on which move the rollers 69 carried by the arms 70. The arms 70 have bearings 71 affixed to a shaft 72 journaled in the bearings 73, which latter bearings are supported from the pedestal 66. One of the arms 70 is provided with a socket 74 for a rod or handle 75'. This handle gives leverage for raising the arms 70 and the container 61. One of the arms 70 is formed with a segment 75 against which the beveled nose 76 on the cross bar 77 of a latch device is adapted to engage. The cross bar 77 is carried upon arms 78 which straddle the rear lower end portion of the segment when the latter is in the rear position shown in Figure 13. The arms 78 form a bell-crank with the treadle or foot piece 79. The bell-crank is pivoted or fulcrumed on the pedestal as indicated at 80.

A modification of this latch device is illustrated in Figure 14 where the segment 75^a is shown as 40 carrying a trailing latch or dog 81 pivoted at 82 on the segment and having its beveled or rounded nose 83 wiping along the upper surface of the pedestal 66 which is provided with one or more locking projections 89 having abrupt shoulders 45 and rounded backs.

The reservoir or tank 61 will tend to descend by gravity of its own weight but preferably one or more weighted rings 85 are placed over the tank, resting on lugs 86. In the use of the device, the reservoir, when elevated to substantially the position shown in Figure 13, is filled with lubricant or grease and the cover 64 restored. The weights 85 will tend to bear the tank 61 downwards, thus forcing out the grease through the 55 pipe 50 to the pump device. Thus the grease or lubricant in the reservoir 61 is maintained under a constant pressure which is tending to force the grease out of the reservoir and into the pumping device.

When the reservoir 61 is exhausted, that is when it has reached the lower limit of its downward movement, as illustrated in dotted lines in Figure 13, then the cover 64 is removed to break any possible vacuum that might form in the reservoir as the container 61 was elevated. Thereupon a rod 75' is introduced into the socket 74 and with the leverage thus gained, the arms 70 are swung up about the shaft 72 thus causing the rollers 69 to lift the container 61. In executing this movement the locking device or latch shown in Figure 13 will by reason of its weight 70 follow the rear edge of the segment 75 until, when the container is fully elevated, the arms 78 of the latch will lie substantially horizontally on 75

the pedestal and the nose 76 will engage against the rear edge of such segment. Thus the tank 61 will be held elevated without the use of the operator's hands which may be left free to refill the reservoir. By use of the foot-piece 79 the latch may be lifted after the reservoir is filled and the cover 64 restored.

In accordance with Figure 14, the latch 81 will be trialed along as the segment is rotated until it arrives at substantially the dotted line position when the tank 61 is fully elevated. The latch may be kicked out whenever the operation of the device is to be resumed.

The pressure of the lubricant entering the pumping device will raise the plunger 52 and close the valve 45. In this action it will be aided by the coil spring 46. When a wheel 17 of a car passes over the rail 15, the tread of the wheel, which is wide enough to extend upon the outside of the rail head, will encounter the button 56, depressing the same to the position shown in Figure 9, it being understood that ordinarily the grease pressure and the spring 46, or either of them, will maintain the button 56 in the position shown in Figure 8 where the same is raised above the plane of the rail tread.

As the wheel passes over the rail and over the button 56 it causes the button 56 and the plunger 52 to be depressed, thus ejecting a charge of grease through the port 48 and valve 45 which has been opened by this action. The grease thereupon flows out of the lower chamber 41, through the pipe connection 21' and to the applicator. When the wheel has passed over the button 56 the spring 46 and the lubricant pressure will tend to restore the parts upwardly and close the valve 45. This valve 45 keeps the reservoir pressure from constantly forcing the lubricant out through the slot in the applicator.

The lubricant, from the pipe 21' enters the body chamber 22, which chamber may be molded within the body 21 or otherwise produced therein. The grease has open and immediate access from the chamber 22 to the slot 24. By adjusting the screws 38 this grease may be applied to any elevation upon the rail head.

The device produces a continuous sheet or ribbon of grease applicable to all parts of a designated lineal section of rail and to continuous and uninterrupted portions of the wheel flange passing along such rail head, the application of the lubricant being thus surer and the efficiency of the device accordingly increased.

As shown in Figures 5 and 6, the lip, composed of the inner and outer walls 23 and 25 may be

adjusted vertically so that the open upper delivery mouth thereof is disposed at a height slightly above the lowermost point of the wheel flange 20. The lip may also be adjusted to be even with or lower than the lowermost point of the wheel flange 20.

It is obvious that various changes and modifications may be made in the details of construction and design of the above specifically described embodiment of this invention without departing from the spirit thereof, such changes and modifications being restricted only by the scope of the following claims.

What is claimed is:—

1. An applicator for track lubricators, comprising a body portion adapted to fit against the side of a rail and provided with a longitudinal chamber therein for the reception of lubricant under pressure, said body portion having one wall of said chamber extending upwardly and provided with a lip constituting a continuation of said wall adapted to lie against the head of the rail, and a plate member detachably seated in the upper side of the body portion spaced from said wall and projection to provide therewith a slot extending along the side of the rail.

2. An applicator for track lubricators comprising a body portion having a lubricant receiving chamber extending lengthwise therein and provided with an upstanding lip adapted to lie against the side of a rail head, said lip and chamber having a continuous vertical wall for feeding the lubricant upwardly from the chamber to the lip, a wear plate fitted upon the upper part of the body portion in spaced relation to the lip to provide therewith a slot for the passage of lubricant, and a rib carried upon the lower edge portion of the wear plate removably seated in the upper face of the body portion to hold the lip thereto.

3. An applicator for track lubricators comprising a body portion, means for securing the body portion against the side of a rail, said body portion having a chamber therein for receiving lubricant under pressure and provided with an upstanding longitudinal lip extending from the outer wall of said chamber and adapted to lie against the side of a rail head, a wear plate having a bead upon its lower edge removably seated in the top of the body portion to hold the wear plate thereto and in spaced relation to the lip above said chamber, whereby lubricant under pressure may pass directly into the space above the chamber between the lip and the wear plate.
